Primary Examiner — John R Yeh(74) *Attorney, Agent, or Firm* — DAY PITNEY LLP;
George N. Chaclas; Anthony A. Kassas(57) **CLAIM**

The ornamental design for a scraper head assembly as shown and described.

DESCRIPTION

FIG. 1 is a front, top, right side isometric view of a scraper head assembly in accordance with my design;

FIG. 2 is a front elevation view of scraper head assembly as shown in FIG. 1;

FIG. 3 is a rear elevation view of scraper head assembly as shown in FIG. 1;

FIG. 4 is a right side elevation view of scraper head assembly as shown in FIG. 1;

FIG. 5 is a left side elevation view of scraper head assembly as shown in FIG. 1;

FIG. 6 is a top plan view of scraper head assembly as shown in FIG. 1;

FIG. 7 is a bottom plan view of scraper head assembly as shown in FIG. 1; and,

FIG. 8 is rear, bottom, left side isometric view of scraper head assembly as shown in FIG. 1.

The broken lines illustrate portions of the scraper head assembly which form no part of claimed design.
